UNITED STATES PATENT OFFICE.

THOMAS D. ROSS, OF DALLAS, TEXAS.

COTTON CLEANER.

Application filed August 11, 1921. Serial No. 491,600.

To all whom it may concern:

Be it known that I, THOMAS D. Ross, a citizen of the United States, residing at Dallas, in the county of Dallas and State of Texas, have invented certain new and useful Improvements in Cotton Cleaners, of which the following is a specification.

This invention relates to new and useful improvements in cotton cleaners.

10 The object of the invention is to provide a cotton cleaner which will handle any kind of staple or lint cotton of all grades, as well as seed cotton, bolls, waste lint from gins and damaged cotton. A further object 15 of the invention is to provide a cleaner which will clean any kind of cotton and separate the fibers at the same time so as to discharge it free from foreign matter, mats and in the best condition.

20 Another object is to provide a cotton cleaner which removes the dust and at the same time opens up and disintegrates the charge of cotton which is introduced into the cleaner. This permits the air to pass 25 freely thru the cotton, and offers a superior means of cleaning and disintegrating, particularly cotton of a low staple and particularly bats which are very dirty.

A construction designed to carry out the 30 invention will be hereinafter described together with other features of the invention.

The invention will be more readily understood from a reading of the following specification and by reference to the accom-

35 panying drawings, in which an example of the invention is shown and wherein:

Fig. 1 is a side elevation of a cleaner constructed in accordance with my invention, a portion being broken away to illustrate the cleaning chamber,

Fig. 2 is a transverse vertical sectional view on the lines 2—2 of Fig. 1,

Fig. 3 is a perspective in detail showing the manner of fastening the cleaner blades 45 on the shaft,

Fig. 4 is a plan view with the cover section of the chamber removed, and

Fig. 5 is an underside view.

In the drawings the numeral 10 designates a base frame on which end standards 50 11 are suitably mounted. The end standards 11 support vertical end walls 12 which are connected with side walls 13, said walls preferably being formed of sheet metal 55 and suitably secured to the standards. The side and end walls form a housing which has

a laterally directed flange 14 along its upper side which receives the side flanges 15 of a semi-cylindrical cover or hood 16, which is closed at its end and registers with the 60 end walls 12.

At one end the cover is provided with a feed hopper 17 opening into the cleaner chamber within said cover. This hopper is placed at one side just above the flange 15. 65 The cleaner chamber has a concaved bottom disposed within the housing, one half of which bottom is formed of foraminous material such as wire netting 18, while the other half 19 is preferably formed of sheet 70 metal and is imperforated except for a discharge opening 20 at the end opposite to the hopper 17. The chamber is cylindrical in shape and a longitudinal beater shaft 21 extends therethru, said shaft being suitably 75 supported in bearing boxes at the upper end of the standards 11. A pulley 22 is mounted on one end of the shaft and a similar pulley 23 is mounted on the other end of the shaft. Fast and loose pulleys 24 and 25 are also 80 mounted on the shaft for driving the same. A plurality of beater blades 26 are mounted on the shaft and disposed radially. These blades are positioned so that their outer ends are co-ordinated in the form of a helix as is 85 clearly shown in Fig. 1. Thus when the beater is revolved this arrangement causes the cotton to be conveyed from the hopper end to the opposite end of the cleaner chamber.

90 The manner of fastening the beater blades on the shaft 21 is simple and effective, but may be changed without departing from the spirit of the invention. Each blade is twisted upon itself so as to provide a shank 27 at right angles to the rest of the blade. This shank is rolled at its inner end to form an eye 28 thru which the shank of a hook bolt 29 is passed and held by a nut 30. The hook of the bolt 29 is engaged over the shank 100 of the opposite beater blade which is disposed upon the other side of the shaft. By directing the blades in the opposite directions and disposing their hook bolts on opposite sides of the shaft as is shown in 105 Fig. 3, the blades will be securely held in position. By loosening the nut 30 any blade may be removed and replaced or repaired. The ends of the blades revolve in proximity to the cover 16 and the concaved 110 bottom of the chamber. Studs 31 project downwardly from the center of the cover

and are disposed so that the blades pass therebetween. Similar studs 32 are mounted in the side walls immediately below the flanges 14 and also project between the 5 blades. These studs are preferably screw threaded and are provided with lock nuts 33 for holding them in position.

Under the screen 18 a trough 34 is disposed longitudinally of the housing, while 10 a similar trough 35 is disposed under the bottom 19. These troughs have their inner sides meeting along the center of the housing and contacting at the intersection of the parts 18 and 19. By this arrangement 15 all dust and dirt which is separated from the cotton passes thru the screen 18 into the trough 34, while the cotton is conveyed to the end of the chamber and discharged thru the opening 20 into the trough 35. At the 20 end of the trough 34 a suction fan 36 is arranged and draws the dirt and foreign matter from the trough 34 and discharges it thru a spout 37 in the side of the housing. At the opposite end of the trough 35 a suction 25 fan 38 is arranged and is provided on its upper side with a discharge spout 39 extending thru the side wall 12. The end wall 12 is provided with an opening 40 which admits air to the trough 35 at the end 30 opposite to the fan 38, said opening 40 being below the opening 20. This opening 40 admits air so that the cotton may be easily conveyed along the bottom of said trough.

The fan 36 is provided with a pulley 41 35 which is driven by means of a belt 42 from the pulley 23; while the fan 38 is provided with a pulley 43 driven by a belt 44 from the pulley 22. By this arrangement motion is transmitted to the beater shaft 21 which 40 in turn operates both of the fans. It will be noticed that the fans are disposed at opposite ends of the machine and this arrangement gives the cotton time to pass thru the cleaning chamber and freely discharge down thru the opening 20 into the trough 35 in 45 which it may accumulate and prevent choking of the cleaner.

This cleaner is designed to handle linters which is had from the gins at oil mills, seed 50 cotton, which is cut before it is ginned; bolls, which is cotton in dry bolls which has not opened; waste lint from cotton gins; waste and damaged cotton such as is injured by water and by picking from the bale in 55 sampling etc., and all kinds of bats and wadded cotton such as is reclaimed from old mattresses and the like. The charge is fed in a suitable manner thru the hopper 17 and is immediately attacked by the 60 revolving beater blades 26, which carries the cotton around the chamber and drags the fibers between the studs 31 and 32. This causes the cotton and etc., to be quickly broken up and disintegrated so that the air 65 which is drawn in thru the hopper 17 by

the fan 36 immediately removes the dust. The helical arrangement of the blades causes the cotton to travel toward the opposite end of the cleaning chamber. By quickly disintegrating the cotton the dust is freed together with other foreign matter and is drawn down thru the screen 18. This is very important because the beater being rapidly revolved breaks up the charge in a very efficient manner and carries out a 70 thorough cleaning operation.

Repeated tests have shown that when the cotton reaches the opening 20 it is thoroughly cleaned and is discharged down thru said opening in this state into the trough 35. 80 The fan 38 carries the cotton out of the trough and discharges it thru the spout 39.

What I claim, is:

1. In a cotton cleaner, a cleaner chamber having an inlet at one end and an outlet at 85 the other end, a cotton receptacle extending under the chamber communicating with the outlet, a dust receptacle under the chamber, said chamber having a foraminous bottom section disposed over the dust receptacle, and a revolving beater mounted in the chamber, that portion of the bottom of the chamber lying over the cotton receptacle except the outlet being imperforate.

2. In a cotton cleaner, a cleaner chamber 95 having an inlet at one end and an outlet at the other end, a cotton receptacle under the chamber communicating with the outlet, a dust receptacle under the chamber, said chamber having a foraminous bottom section 100 disposed over the dust receptacle, and a revolving beater mounted in the chamber, that portion of the bottom of the chamber lying over the cotton receptacle except the outlet being imperforate, a suction discharge fan 105 connected with the dust receptacle, and a suction discharge fan connected with the cotton receptacle.

3. In a cotton cleaner, a cleaner chamber having an inlet at one end and an outlet at 110 the opposite end, the bottom of the chamber being concaved and having a foraminous section along one side and an imperforate section along the other side, the outlet being in the imperforate section, a revolving beater 115 mounted in the chamber, and means for segregating the dust and cotton discharging from the chamber and delivering same at separated points.

4. In a cotton cleaner, a cleaner chamber 120 having an inlet at one end and an outlet at the opposite end, the bottom of the chamber being concaved and having a foraminous section along one side and an imperforate section along the other side, the outlet being 125 in the imperforate section, a revolving beater mounted in the chamber, a cotton trough extending longitudinally under the imperforate bottom portion of the chamber and the outlet, a suction discharge fan at the end of 130

- the cotton trough opposite the outlet of the chamber, a dust trough underlying the foraminous portion of the chamber, and a suction discharge fan at the end of the dust trough opposite to the inlet of the chamber.
5. In a cotton cleaner, a cleaner chamber having an inlet at one end and an outlet at the opposite end, the bottom of the chamber being concaved and having a foraminous section along one side and an imperforate section along the other side, the outlet being in the imperforate section, a revolving beater mounted in the chamber, means for segregating the dust and cotton discharging from the chamber and delivering same at separated points, inward projections on the inner surface of the chamber, and a beater comprising radial blades having their ends passing between said projections.
- 10 6. In a cotton cleaner, a housing, a cylindrical cleaner chamber along the top of the housing, a feed hopper at one end and one
- 15 side of the chamber, said chamber having a concaved bottom formed of an imperforate section along one side having a cotton discharge opening at its end opposite from the feed hopper and a screen section along the opposite side, a cotton trough under the imperforate bottom and the cotton outlet, a suction fan at the end of the cotton trough 20 opposite from the outlet, a dust trough under the screen, a suction fan at the end of the dust trough opposite from the feed hopper, said troughs having their adjacent walls rising to the bottom of the chamber and confining the screen to the dust trough, a beater shaft passing thru the chamber, inwardly projecting studs mounted on the inner surface of the chamber, and radial beater blades mounted on the shaft and having their outer 25 ends passing between the studs.
- 20 6. In a cotton cleaner, a housing, a cylindrical cleaner chamber along the top of the housing, a feed hopper at one end and one
- 30 side of the chamber, said chamber having a concaved bottom formed of an imperforate section along one side having a cotton discharge opening at its end opposite from the feed hopper and a screen section along the opposite side, a cotton trough under the imperforate bottom and the cotton outlet, a suction fan at the end of the cotton trough 35 opposite from the outlet, a dust trough under the screen, a suction fan at the end of the dust trough opposite from the feed hopper, said troughs having their adjacent walls rising to the bottom of the chamber and confining the screen to the dust trough, a beater shaft passing thru the chamber, inwardly projecting studs mounted on the inner surface of the chamber, and radial beater blades mounted on the shaft and having their outer 40 ends passing between the studs.

In testimony whereof I affix my signature.

THOMAS D. ROSS.
